The ornamental design for a combination actuator and hood for dispensing gel material, as shown and described.

DESCRIPTION

FIG. 1 is an exploded left side elevational view of a combined actuator and hood for dispensing gel material showing my new design, undisclosed opposite side being a mirror image;

FIG. 2 is a front elevational view thereof;

FIG. 3 is a rear elevational view thereof;

FIG. 4 is a top plan view of the hood, shown for clarity of illustration;

FIG. 5 is a top plan view of the actuator, shown for clarity of illustration;

FIG. 6 is a bottom plan view of FIG. 4;

FIG. 7 is a bottom plan view of FIG. 5; and,

FIG. 8 is a front elevational view.

The broken away section is shown due to indeterminate length of the container.
